UNITED STATES PATENT OFFICE.

ERNST WERNER, OF OBERLANGENBIELAU, GERMANY.

CALENDER.

Application filed December 16, 1927, Serial No 240,597, and in Germany November 13, 1926.

This invention relates to calendering machines having a plurality of calendering rollers adapted to operate upon superimposed layers of fabric and to give the fabric a peculiar appearance.

This use of the calendering rollers makes it possible for the fabric to be refined in an uninterrupted operation.

Now as the web of the fabric during each calendering operation passes one roller with one of its faces towards the roller and the next roller with the aforementioned face away from the roller, the fabric will be drawn. Compensation must, therefore, be made for the drawing before the web enters the calendering rolls again. Heretofore this compensation has been secured by mounting the upper guide rollers on spring-actuated swing levers, the lower guide rollers being adjusted by the operator. This arrangement limits the maximum speed of the web during operation to 40 meters per minute and the number of layers passing through the calendering rolls to 6. As is well known, greater economy can be attained by increasing the speed of the web and a better calendering of the fabric can be obtained by having more layers of the web treated simultaneously.

Attempts have been made in the past to eliminate the drawbacks pointed out above, but have met with comparatively little success.

Now the object of this invention is to overcome the above limitations and to compensate for the longitudinal drawing of the web of fabric to a greater extent than has been done heretofore.

To achieve this object I propose to fixedly arrange the upper guide rollers in pairs one under the other. The web of fabric in being guided past the rollers forms a slack between each pair. I further propose to hang a third roller in each slack of the web, the third roller having a free vertical movement.

As a result of my arrangement, the calendering machine can operate without disturbance upon 10 or more layers of web simultaneously at a speed of 70 to 80 meters per minute.

A side view of an embodiment of the subject matter of this invention is illustrated by way of example in the accompanying drawing.

The calendering machine illustrated comprises eight calendering rollers (1 to 8)

mounted for rotation in a frame 9. A plurality of guide rollers 10 are arranged in staggered relation to one another, as shown, at the level of roller 8. Rollers 11 corresponding to rollers 10 are also arranged in staggered relation at the level of roller 1. Just to the side and underneath each guide roller 10 is an intermediate guide roller 12. The web of fabric enters the calendering machine at 13, passes over a roller 14, and travels through rollers 1 to 8 from bottom to top. The web portion 18 upon leaving the calendering rollers passes over the outermost guide roller 10 and appurtenant roller 12, forming a slack between the two, and is led back over the respective roller 11 and lowermost roller 15 to the lowermost calendering roller 1.

Now the fabric travels a second time through the calendering machine. Portion 19 of the web denotes that part which has just left the calendering rollers for the second time. Portion 19 is led over the next to the last guide roller 10 and appurtenant roller 12, forming a slack between the two, then the respective rollers 11 and 15 back to the lowermost calendering roller 1.

In this manner, the fabric travels through the calendering machine again and again in ten rounds (18 to 27) and is finally led from the upper calendering roller 8 and rewound on reel 16.

Compensating rollers 17 are hung in the slack portions of the web formed between the rollers 10 and 12, are free to move in a vertical direction, and may be guided in any desired manner in the machine frame.

As the entire space between the upper and lower guide rollers 10 and 11 is at disposal for the formation of slacks, a compensation may be made between the successive calendering operations which corresponds to twice the distance between the upper and lower guiding rollers. In this way, 10 or more web layers may be passed between the calendering rollers without any disturbance in operation arising and without the fabric being undesirably drawn. The frictional resistances are extremely low, so that only a small expenditure of power is required to drive the machine.

Due to the fact that 10 or more layers of web travel in superimposed order through the calendering rollers, instead of 5 or 6 which was the maximum limit in machines heretofore, a better effect is obtained. My described means for compensating for the slack in the

web between layers also makes it possible for the machine to travel at a speed double that of known machines.

I wish it understood that my invention is not limited to any specific construction or arrangement of the parts except in so far as such limitations are specified in the appended claims.

Having thus described my invention, I claim:

1. The combination in a calendering machine of a set of calendering rollers adapted to operate on superimposed layers of a continuous web of fabric, a set of upper guiding rollers and a set of lower guiding rollers, one of each set of upper and lower guiding rollers being associated with a corresponding layer of said web and adapted to guide said layer in its course from one passage through said calendering rollers to the next, an intermediate guide roller arranged immediately underneath each of said upper guiding rollers and receiving the web coming from the appurtenant upper guiding roller in such a way that a slack is formed in the web between it and said appurtenant upper guiding roller, and means for compensating for said slack.
2. In a machine of the class described, a set of calendering rollers for operating upon superimposed layers of a continuous web, a set of upper guiding rollers, each of said guiding rollers receiving one of said layers as it leaves said calendering rollers, a set of intermediate guiding rollers arranged in staggered relation underneath said upper guiding rollers, each of said last-named rollers receiving one of said layers after it passes the appurtenant upper guiding roller, a set of lower guiding rollers, each adapted to guide one of said layers from a respective intermediate guiding roller back to said calendering rollers, and another set of rollers, each of said last-named rollers being hung in a loop formed by the slack in the web between said upper and intermediate guiding rollers.

3. In a machine of the class described, a set of calendering rollers for operating upon superimposed layers of a continuous web, an upper guiding roller receiving said web as it leaves said calendering rollers, an intermediate guiding roller arranged immediately below said upper guiding roller and receiving said web after it passes said upper guiding roller, a lower guiding roller for guiding said web from said intermediate roller back to said calendering rollers, and a roller hung in the loop of said web formed between said upper and intermediate guiding rollers.

4. A machine according to claim 1, in which said means comprises a roller hung in the loop formed by said slack and having a free vertical movement.

In testimony whereof the foregoing specification is signed.

ERNST WERNER.
